A. C. BADGER.
STERILIZING HOPPER.
APPLICATION FILED DEC. 21, 1909.

Patented July 19, 1910.

UNITED STATES PATENT OFFICE.

ARTHUR C. BADGER, OF NEWTON CENTER, MASSACHUSETTS, ASSIGNOR TO E. B. BADGER & SONS COMPANY, OF BOSTON, MASSACHUSETTS, A CORPORATION OF MASSACHUSETTS.

STERILIZING-HOPPER.

964,838.

Specification of Letters Patent. Patented July 19, 1910.

Application filed December 21, 1909. Serial No. 534,352.

To all whom it may concern:

Be it known that I, ARTHUR C. BADGER, of Newton Center, in the county of Middlesex and State of Massachusetts, have invented 5 certain new and useful Improvements in Sterilizing-Hoppers, of which the following is a specification.

This invention relates to apparatus for sterilizing or disinfecting excreta infected 10 with germs of typhoid fever and other infectious diseases, so that the excreta will not be a source of danger when discharged into a sewer or elsewhere.

The invention is embodied in a sterilizing 15 hopper comprising a steam jacket forming the wall of a sterilizing receptacle, a valve seat in close proximity to the lower end of the steam space of said jacket, and a movable gate valve having a liquid tight fit 20 on said seat and forming a temporary bottom for said receptacle, means being provided for preventing an accumulation of water of condensation in the lower end of the steam chamber, so that the entire inner 25 surface of the steam jacket down to the valve is utilized as a heated sterilizing surface adapted to thoroughly heat and boil diluted excreta deposited in the receptacle, the sterilized material being discharged by 30 gravitation when the valve is opened.

Of the accompanying drawings, forming a part of this specification,—Figure 1 represents a vertical section of a sterilizing hopper embodying my invention. Fig. 2 represents a section on line 2—2 of Fig. 1. Fig. 3 represents a section on line 3—3 of Fig. 2. Fig. 4 represents a section on line 4—4 of Fig. 1.

The same reference characters indicate the 40 same parts in all the figures.

My improved hopper comprises a main receiving portion 12 preferably of tapering form, and a neck portion 13 through which material deposited in the main portion is 45 discharged from the hopper. The said portions are double-walled, and contain a steam space 14. For convenience, I will refer to the entire portion of the hopper that contains the steam space as a steam jacket.

50 15 represents a valve seat which is substantially parallel with the lower end of the steam jacket, and is in close proximity thereto, the valve seat being preferably made separately from the steam jacket, and forming 55 a part of a valve chamber 16, in which

is a gate valve 17 adapted to have a liquid-tight fit upon the valve seat, so that when the valve is closed it constitutes the bottom of a sterilizing receptacle, the wall of which is formed by the steam jacket, the heated 60 surface of the latter extending downwardly practically to the upper surface of the valve.

The reduced lower portion of the steam jacket is preferably of cylindrical form, and is fitted in a cylindrical socket or recess 18 65 formed on the upper side of the valve chamber 16, said socket having a flange 19 to which is bolted a flange 20 formed on the exterior of the steam jacket. 21 represents a steam inlet and 22 an outlet for exhaust 70 steam and water of condensation, said inlet and outlet being located above the lower end of the steam jacket and preferably formed in the flange 20.

The inlet 21 opens directly into the annular steam space 14. The outlet 22 is extended downwardly by means of a short inserted tube 22' which is screwed into a bridge 23 formed between the inner and outer walls of the steam jacket, and extends 75 downwardly nearly to the lower end of the steam space, the lower end of the tube 22 constituting an intake 22^a into which water of condensation accumulating at the lower end of the steam space is forced by the steam 80 pressure. Provision is therefore made for preventing any such accumulation of water of condensation in the lower end of the steam jacket as would impair the heating effect of the inner wall of the jacket, the 85 actively heated inner wall of the jacket extending downwardly practically to the valve seat so that when the valve is closed to form a temporary sterilizing receptacle, all the material in said receptacle is subjected 90 to the same degree of heat. The tube 22' 95 may be inserted through an opening provided for its reception in the lower end of the neck portion 13, said opening being subsequently covered by a closure formed to 100 occupy the opening and secured in place by brazing or otherwise, the said closure forming a part of the lower end of the neck portion 13.

Prior to the sterilizing operation the material is sufficiently diluted with water to enable it to be boiled by the heat radiated into it from the inner wall of the steam jacket. Owing to the fact that the active 105 inner surface of the steam jacket extends 110

practically to the bottom of the charge of diluted material, a thorough and efficient circulation is set up, so that all parts of the charge are thoroughly and uniformly boiled, 5 complete sterilization being the result. When the charge of material has been sufficiently sterilized, the valve is opened, and the charge is permitted to escape by gravitation through an outlet 25 in the lower end 10 of the valve chamber. Said outlet may communicate with a sewer or other receptacle for the discharge of material. The valve 17 is provided with a stem 26 with which may be connected a suitable operating lever 27.

I claim:

1. A sterilizing hopper comprising a steam jacket forming the wall of a sterilizing receptacle, a valve seat at the lower end of 20 the jacket and in close proximity to the steam space thereof, and a valve adapted to close on said seat and form the bottom of said receptacle, the steam outlet of the jacket being arranged to conduct away practically 25 all water of condensation from the lower end of the jacket whereby the entire inner surface of the jacket is utilized as a heating surface extending substantially to the valve.
2. A sterilizing hopper comprising a steam jacket forming the wall of a sterilizing receptacle, said jacket having a steam inlet and an outlet for steam and water of condensation, a valve seat located in close proximity 30 to the lower end of the steam space in the jacket, and a valve adapted to close on said seat and constituting, when closed, the bottom of the said sterilizing receptacle, the outlet of the jacket being arranged to 35 cause the expulsion of practically all the water of condensation from the jacket by 40

steam pressure therein, whereby the entire lower portion of the inner surface of the jacket is utilized as a heating surface extending substantially to the valve. 45

3. A sterilizing hopper comprising a steam jacket forming the wall of a sterilizing receptacle, and a valve chamber below the jacket having a valve seat in close proximity to the steam space of the jacket, a 50 valve adapted to close on said seat and form the bottom of said receptacle, and an outlet below the valve.

4. A sterilizing hopper comprising a steam jacket having a steam inlet and an outlet 55 for steam and water of condensation, both located above the lower end of the jacket, the said outlet having its intake substantially at the bottom of the steam space so that practically all the water of condensation 60 is expelled by steam pressure through the outlet, a valve seat at the lower end of the jacket and in close proximity to the steam space thereof and a valve adapted to close on said seat. 65

5. A sterilizing hopper comprising a steam jacket having a steam inlet and an outlet for steam and water of condensation both located above the lower end of the jacket, the intake of the outlet being substantially 70 at the bottom of the steam space of the jacket, a valve chamber having a socket which receives the lower end of the jacket, a valve seat in close proximity to the lower end of the jacket, a valve adapted to close 75 on said seat, and an outlet below the valve.

In testimony whereof I have affixed my signature, in presence of two witnesses.

ARTHUR C. BADGER.
